DOMESTIC IRONER

Luther Ringer, Union Springs, N. Y., assignor
to Easy Washing Machine Corporation, Syra-
cuse, N. Y., a corporation of Delaware

Application November 29, 1929, Serial No. 410,485

6 Claims. (Cl. 38—61)

This invention relates to a new and improved domestic ironer.

My invention is illustrated in connection with an ironing machine which may be substituted for the wringer on a mechanical clothes washing machine and which will be driven from the source of power which operates the mechanical clothes washing machine.

The principal object of my invention is to provide an ironing machine of the roll and shoe type which incorporates certain features relating to the roll and shoe operating mechanism that make the machine convenient and easy to operate, and capable of especially advantageous use, particularly in that not only may conventional roll and shoe ironing and pressing with the roll stationary be performed, but the rotation of the roll may be stopped during a roll and shoe ironing operation while the shoe is in contact with the roll without otherwise interrupting the ironing operation, which may be resumed simply by again starting the roll.

Other objects and advantages relate to the size, shape and arrangement of parts, all as will more fully appear from the following description taken in connection with the accompanying drawings in which:

Figure 1 is a top plan view of my improved ironer.

Figure 2 is a side elevation, partially broken away and partially in section, of my ironer in position in the wringer post of a washing machine.

Figure 3 is a section on line 3—3 of Figure 2.

Figure 4 is a section, partially broken away, on line 4—4 of Figure 3.

Figure 5 is a section on line 5—5 of Figure 4.

Figure 6 is a section on line 6—6 of Figure 5.

Figure 7 is a section, partially broken away, on line 7—7 of Figure 4.

Figure 8 is a section on line 8—8 of Figure 7.

Figure 9 is a section on line 9—9 of Figure 7.

Figure 10 is a section on line 10—10 of Figure 9.

Figure 11 is a section on line 11—11 of Figure 1.

Figure 12 is a section on line 12—12 of Figure 1.

Figure 13 is a section, partially in full, on line 13—13 of Figure 2.

My ironer 1 comprises a gear casing 2 having a depending tubular boss 3. On one end of casing 2 is provided a laterally extending tubular boss 4 in which is positioned a laterally extending tubular member 5.

In member 5 and rotatably mounted therein is a tubular shaft 6.

On the outer end of shaft 6 is secured an ironer shoe support. Such support may be of different

designs but for the purpose of explaining my invention I have here shown a new and improved ironer shoe support which has been disclosed and claimed by me in my co-pending application for Ironer filed October 9, 1929, Serial No. 398,386, which issued into Patent No. 1,865,048, dated June 28, 1932.

On the outer end of shaft 6 is rotatably mounted a yoke 7, (Figure 11).

On the upper end of yoke 7 is pivotally mounted a shoe support 8 as by a pivot pin 9 to the forward end of which and above the pivot 9 is secured the shoe 10.

Shoe 10 is curved in cross section with its inner face conforming to the contour of the ironer roll 11 hereinafter to be described.

Within the shoe 10 a resistance heating unit 12 is connected as by a cable (Figure 1) 13 to a source of potential not shown.

A spring 14 has its upper end secured to the rear face of shoe 10 and has its lower end bearing against the inner face of yoke 7 to hold shoe 10 in the raised position when the same is out of contact with roll 11.

Between the sides of yoke 7, and secured to shaft 6 as by a pin 15, I provide a member 16 which has its outer end provided with an aperture 17 through which extends the shaft 18.

The lower end of shaft 18 is provided with a transverse pin 19 normally abutting against a curved guide 20. The upper end of shaft 18 is provided with an adjusting nut 21, and spiral spring 22 has one end abutting against nut 21, and has its lower end abutting against member 16 to normally urge shaft 18 to the raised position with pin 19 abutting against guide 20.

On the lower end of yoke 7 is pivotally mounted as by a pivot 23, a dog 24 which carries on its upper end a hooked portion 25 adapted to normally engage pin 19 to lock yoke 7 to member 16.

A spring 26 has one end secured to member 16 and has the other end secured to dog 24 to releasably hold hook 25 in registration with pin 19.

With the parts in the normal position just described any movement transmitted to member 16 through shaft 6 will be transmitted to yoke 7.

On the upper end of yoke 7 is pivotally mounted on the pivot pin 9, a bell crank 27.

In the upper arm 28 of bell crank 27, I provide a vertically extending shaft 29 carrying a knob 30 on its upper end. The other arm 31 of bell crank 27 is in engagement with the upper end of a shaft 32 slidably mounted in the upper end of yoke 7 and having its lower end pivotally mounted in the outer end of dog 24.

The lower end of bell crank 27 has a stop 33 which abuts against the yoke 7 to limit the movement of bell crank 27 in one direction. With the parts in the position just described, member 16, yoke 7 and shoe 10 will be actuated as a unit through movement of shaft 6, which movement will be hereinafter described, but which is adapted to move shoe 10 towards and from roll 11.

When it is desired to release yoke 7 from member 16 so that yoke 7 carrying shoe 10 may be moved about shaft 6 to carry shoe 10 out of engagement with roll 11, the bell crank 27 is moved about its pivot by means of shaft 29 and this movement will cause the end 31 of bell crank 27 to move downwardly carrying before it shaft 32.

The downward movement of shaft 32 will cause dog 24 to be moved about its pivot 23 to carry hook 25 out of engagement with pin 19 to break the connection between yoke 7 and member 16.

After this initial movement has been completed, shaft 29 may be moved still further in the same direction causing yoke 7 to pivot about shaft 6 to move shoe 10 out of engagement with the roll 11.

The position of parts after this movement of shaft 29 has been completed is indicated in dotted lines on Figure 11.

For the purpose of limiting the movement of yoke 7 just described, I provide on yoke 7 (Figure 12) a pin 34 which is adapted to contact with a finger 35 carried on tubular member 5.

With the parts in the last described position indicated in dotted lines it will be noted that the hook 25 is beneath but in the path of movement of the pin 19.

When the latter is thereafter moved downwardly through the rotary movement of member 16 on shaft 6, which movement of member 16 subsequently takes place through the operation of the mechanism about to be described, pin 19 will ride downwardly past hook 25 due to the fact that it will force dog 24 about its pivot against the action of spring 26.

After pin 19 has moved downwardly beneath hook 25, spring 26 will cause dog 24 to move about its pivot to bring hook 25 into registration with pin 19 so that the parts will again become locked in the initially described operative position, and any further movement of member 16 will cause yoke 7 and shoe 10 to be moved with it as a unit.

A secondary laterally extending tubular boss 36 is provided on casing 2. A tubular supporting shaft 37 has one end secured in boss 36 and extending outwardly therefrom.

The ironing roll 11 (Figure 4) has secured in its inner end as by screws 38 an annular internal gear 39 provided with a central hub 40 rotatably mounted on shaft 37.

Adjacent the outer end of roll 11 is provided an internally positioned plate 41 carrying a centrally located bearing 42 in which shaft 37 is positioned.

In the outer end of shaft 37 is secured a plate 43 having a centrally located threaded aperture 44.

A disk 45 of greater diameter than the diameter of bearing 42 is secured on the end of shaft 37 as by a screw 46 which is in threaded engagement with plate 43 to hold roll 11 in position on shaft 37.

On the inner face of casing 2 is provided an inwardly extending tubular boss 47 and on face plate 43 of casing 2 and coaxial with boss

47 is provided an outwardly extending tubular boss 49.

A shaft 50 has one end rotatably and slidably mounted in a bearing member 51 carried in boss 49 and has its other end rotatably and slidably mounted in boss 47.

Shaft 50 is less in length than the distance between the outer ends of the apertures in bosses 47 and 49 to permit a limited axial movement of shaft 50 in relation to such bosses 47 and 10 48. (Figure 4.)

A clutch member 52 is secured on shaft 50 as by a key 53. The key-way 54 in member 52 is sufficiently long to permit longitudinal movement therein of key 53. Key 53 is rigidly secured in shaft 50.

A spiral gear 55 is rotatably mounted on shaft 50 and carries on one face a laterally extending hub 56 to which is secured a clutch member 57, as by screws 58, adapted to coact with member 52 in a manner hereinafter to be described.

The opposite face of gear 55 is provided with a plurality of circumferentially spaced and preferably tapered jaws 59.

A spur gear 60 carrying a bearing member 61 is rotatably mounted on shaft 50. On one face of gear 60 is provided a plurality of circumferentially spaced and preferably tapered jaws 62 adapted to coact with jaws 59 on spiral gear 55.

Intermediate gears 55 and 60 is provided in shaft 50 an annular groove 63 in which is positioned a disk 64 which bears against the face of gear 60.

On the face of gear 60 opposite to that on which the jaws 62 are carried is secured an annular member 65 in spaced relation to that face of gear 60.

A spiral spring 66 encircles boss 47 and has one end abutting against casing 2 and the other end abutting against member 65 to normally urge gear 60 towards gear 55 and jaws 62 into engagement with jaws 59.

The end of shaft 50 which is positioned in boss 47 is provided with a recess 67 in which is positioned a spiral spring 68.

Spring 68 has one end abutting against casing 2 and has the other end abutting against the bottom of aperture 67 to normally urge shaft 50 towards boss 49.

On the side of casing 2 is positioned a laterally extending boss 69 in which is journaled a shaft 70. The inner end of shaft 70 (Figure 8) has secured thereto as by a pin 71, a spur gear 72 in mesh with gear 60.

On the outer end of shaft 70 and secured thereto as by a set screw 73 is provided a pinion gear 74 in mesh with an internal gear 39.

On the inner face of casing 2 and coaxial with tubular boss 3 is a vertically extending tubular boss 75 provided with a bearing member 76.

A stub shaft 77 is journaled in bearing 76 and has secured to the upper end thereof, as by a pin 78, a pinion gear 79 in mesh with gear 55. The hub of gear 79 is greater in diameter than the diameter of bearing member 76. Shaft 77 is provided with a shoulder 77' adjacent the lower end of bearing member 76. With this arrangement of parts shaft 77 is held against axial displacement in relation to bearing member 76.

On the lower end of stub shaft 77 is provided a transverse pin 80 (Figure 2) for a purpose hereinafter to be described.

The clutch members 52 and 57 coact in the following way. A curved plate 81 is pivotally

mounted at approximately its center point on to clutch member 52 by means of a pivot pin 82. One end of plate 81 has secured thereto an end of a spiral spring 83, the other end of spiral 5 spring 83 being secured to plate 52 as by a pin 84.

Spring 83 normally urges the end of plate 81 to which it is attached towards clutch member 57.

In parallel relation to plate 81 is pivotally mounted on pivot 82 a dog 85 having a lug 86 10 adapted to register with one of the slots 87 carried on the periphery of clutch member 57.

The end of plate 81 to which spring 83 is attached is offset, as indicated at —a— on Figure 6, to bring it in opposed relation with the end of dog 15 85, a spiral spring 88 being interposed between plate 81 and dog 85.

Plate 81 has a laterally extending lug, indicated at —b— on Figure 6, adapted to contact with the outer face of dog 85 so that when plate 81 is 20 urged by spring 83 towards clutch member 57 dog 85 will be carried with it to bring lug 86 into registration with one of the slots 87.

For the purpose of holding dog 85 out of engagement with clutch member 57 I provide in 25 casing 2 a rock shaft 89 having on its outer end a finger lever 90 pinned thereto as by a pin 91.

On the inner end of rock shaft 89 is provided a depending rock arm 92 with an inwardly curved end 93 adapted to be moved into and out of the 30 path of movement of plate 81.

A coil spring 94 encircles rock shaft 89 and has one end abutting against casing 2 and the other end encircling rock arm 92 to normally hold rock arm 92 in the path of movement of plate 81.

35 The parts are so arranged that rock arm 92 is adapted to contact with either of the ends of plate 81 depending upon the position of clutch member 52 when the rock arm 92 is moved into the path of movement of plate 81.

40 When the rock arm 92 is in the path of movement of that end of plate 81 which is secured to spring 83 and plate 81 comes into contact with rock arm 92, plate 81 will be held against further movement which will cause the same to be 45 moved about the pivot 82 compressing spring 88 and this, in turn, will cause dog 85 to be moved about pivot 82 to carry lug 86 out of engagement with the slot 87 with which it was in registration.

Spring 88 will then expand to further move 50 dog 85 about its pivot 82 to carry lug 86 to a position in spaced relation to clutch member 57 so that there will be no possibility of any contact between dog 85 and clutch member 57 during the operation of the mechanism.

55 If rock arm 92 is in the path of movement of the opposite end of plate 81 and plate 81 comes into contact with rock arm 92 a similar movement will be conveyed to dog 85.

For the purpose of providing a manually operated means whereby clutch member 62 may be held dis-engaged from clutch member 59 independently of the operation of the other parts of the apparatus I provide (Figure 8) a depending shifter arm 94 preferably of spring metal having 60 its upper end secured in casing 2 as by a screw 95 and having its middle portion in registration with the periphery of member 65 and disposed between such member 65 and gear 60.

The lower end of member 94 (Figures 9 and 10) 70 is provided with a slot 96 in which is positioned a pin 97 secured in casing 2. Adjacent pin 97 and in casing 2, I provide a rock shaft 98 having a finger lever 99 secured to the outer end thereof as by a pin 100.

75 On the inner end of rock shaft 98 is secured, as

by a set screw 101, a cam member 102 adapted, when shaft 98 is rocked, to contact with the end of shifting member 94 to move the same laterally to cause gear 60 to be moved axially and out of engagement with gear 55.

When the low side of cam 102 is in registration with the shifting member 94, the different parts of the apparatus will be permitted to function in a normal way but when the high side of cam 102 is brought into registration with shifting member 94 the gear 60 will be held out of engagement with the gear 55 and will remain in that position until the lever 99 is again manipulated. It will be noted that the cam 102 may be operated to disengage clutch member 62 from clutch member 59, or may be operated when clutch member 62 is not in engagement with clutch member 59, thereby enabling the roll to be stopped while the shoe is in engagement with the roll, or when the shoe is away from the roll, enabling the roll to be retained disengaged from its driving mechanism upon subsequent movement of the shoe in engagement with the roll.

For the purpose of providing a means for operating the shaft 6, I provide on the inner end of shaft 6 and secured thereto, as by a pin 103, rock arm 104, a plug 105 being preferably positioned in the end of tubular shaft 6 for the purpose of stiffening the same.

Rock arm 104 has on its outer end opposed jaws 30 106 and 107 between which is positioned a cam member 108 integral with clutch member 52 and eccentric to shaft 50.

When the cam member 108 is in the position shown in heavy lines on Figure 7, the rock arm 35 104 will be in the lowered position which will have caused shaft 6 to be moved in a counter-clockwise movement to bring shoe 10 into registration with roll 11.

When cam 108 is in the position shown in dotted lines on Figure 7, the rock arm 104 will have been moved to the raised position which will have caused shaft 6 to be moved in a clockwise direction to carry shoe 10 out of registration with roll 11.

It will be apparent that the movement of cam 108 and the consequent movement of rock arm 104 will only take place when dog 85 is in registration with clutch member 57 to cause clutch member 52 to be moved as a unit with clutch member 57.

For the purpose of automatically dis-engaging gear 60 from gear 55 intermittently, I provide a cam means coacting with shaft 50 which has been disclosed and claimed by me in United States Letters Patent No. 1,894,242, issued January 10, 1933. Preferably the cam surface is so proportioned that the roll will stop rotating slightly after the time when the shoe leaves the roll, and will start rotating before the shoe re-engages the 60 roll.

The bearing member 51 (Figure 13) is provided on its inner face with a cam surface 109 with which the outer end of key 53 is in contact so that when clutch members 52 and 57 are in engagement to cause the rotation of shaft 50, key 53 65 will move along cam surface 109.

When key 53 moves to the high side of cam surface 109, the shaft 50 will be moved axially to cause collar 64 to bear against gear 60 to move 70 the latter axially against the action of springs 66 and 68 and out of engagement with gear 55 so that roll 11 will come to rest.

When key 53 has moved to the low side of cam surface 109 shaft 50 will be moved axially in the 75

reverse direction through the action of springs 66 and 68 to carry gear 60 towards gear 55 and jaws 62 into registration with jaws 59 to cause gear 60 to be rotated with gear 55 as a unit.

5 In the operation of ironing machines it is desirable that the roll 11 continue to rotate during the time the shoe 10 is in contact with the roll 11 and it is also desirable that the roll 11 come to rest during the time when the shoe 10 is out 10 of engagement with the roll 11 and, in order to effect such movement, the relation of parts is such that when the cam member 108 is in the position where rock arm 104 is in the lowered position with shoe 10 in registration with roll 11, the 15 key 53 will be in registration with the low side of cam surface 109 and gear 60 will be in clutching engagement with gear 55.

When the cam 108 is in the position wherein the crank arm 104 will be in the raised position 20 with the shoe 10 out of registration with roll 11, the key 53 will be in registration with the high side of the cam surface 109 and the gear 60 will have been moved axially out of engagement with gear 55.

25 For the purpose of illustrating the operation of my device, I have here shown a portion of a washing machine 110 having the usual upper and lower frames 111 and 112. (Figure 2.)

A supporting tube 113 has its lower end secured in a gear casing 114 which, in turn, is secured as by bolts 115 to the bottom frame 112.

Supporting tube 113 extends vertically through a yoke 116 secured as by bolts 117 to the top frame 111.

35 In supporting member 113 is positioned a shaft 118 having its lower end extending into gear casing 114 and having secured to such lower end as by a pin 119, a gear 120 which, in turn, is connected through suitable gearing to the motor, 40 not shown, of the washing machine.

On the upper end of shaft 118 is secured, as by a pin 121, a tubular clutch member 122 provided in its upper end with a transverse slot 123 adapted to receive in clutching engagement the lower end 45 of shaft 11 carrying the transverse pin 80.

The relation of parts is such that when my device is in position on the upper end of supporting tube 113, the transverse pin 80 will be positioned in the slot 123 but will not seat in the bottom of such slot so that the weight of my device will be supported entirely on tubular member 113 and no end thrust will be conveyed to shaft 118.

Adjacent the upper end of supporting member 113, I provide a plurality of circumferentially spaced apertures 124. In the lower end of boss 3 (Figure 3) is provided a laterally extending tubular boss 125 in which is slidably mounted a plunger 126. The inner end of plunger 126 is provided with a head 127 adapted to register with an aperture 124.

Encircling shaft 126 and in boss 125 is a spiral spring 128 having one end abutting against head 127 and having the other end abutting against the outer end of boss 125 to normally urge shaft 126 inwardly to bring head 127 into an aperture 124.

For the purpose of providing a convenient means for retracting shaft 126 from an aperture 124 to permit the removal of my device, I provide on the outer end of shaft 126, a knob 129.

The advantages of the apertures 124 in supporting tube 113 consists in the fact that the ironer 1 may be placed in position on supporting tube 113 in a selected one of a plurality of angular

positions in relation to the washing machine 110.

Although I have not here shown a wringer, it will be understood that the wringer to be used with the washing mechanism is adapted to be positioned on tube 113 interchangeably with my ironer 1 so that either the wringer or the ironer may be operated directly from the washing machine mechanism as desired.

It will also be understood that although I have shown and described a specific structure and form and relation of parts as an exemplification of an embodiment of my invention, I do not desire to restrict myself to the exact size or relation of parts as various changes may be made within the scope of the appended claims.

I claim:

1. In an ironing machine in combination, a rotatable roll and a movable shoe, a shaft, a driving gear loosely mounted on said shaft, an eccentric rigidly mounted on said shaft, connections between said eccentric and said shoe for moving said shoe, clutch means between said driving gear and said eccentric for rotating said eccentric and said shaft, a roll drive gear loosely mounted on said shaft for rotating the roll, means comprising a pair of clutch elements for connecting said roll drive gear to said driving gear, means for moving said shaft axially when said first-mentioned clutch elements are engaged to move the shoe away from the roll, and means for disconnecting said second-mentioned clutch elements upon movement of the shaft axially to stop rotation of said roll, and independent means 30 for disconnecting said second-mentioned clutch elements enabling operation of said shoe while the roll is retained stationary.

2. In an ironing machine, in combination, a rotatable roll and movable shoe, a shaft, means comprising a pair of clutch elements mounted on said shaft for moving the shoe toward and away from the roll, means comprising a second pair of clutch elements mounted on said shaft for operating the roll, means for disengaging said second clutch elements when the shoe is moved away from the roll and to engage said second clutch elements when the shoe is moved toward said roll comprising means for moving said shaft axially, and independent means for disconnecting said second mentioned clutch elements enabling operation of said shoe while the roll is retained stationary.

3. In an ironing machine, a rotatable roll and a shoe movable toward and away from the roll, motor means, means comprising a pair of clutch elements for connecting and disconnecting said shoe to and from said motor means to move the shoe toward and away from the roll, driving connections including a second pair of clutch elements to rotate the roll from said motor means, means independent of the movement of the shoe for engaging and disengaging said second clutch elements as an incident to the operation of said first clutch elements, said means enabling both of said pairs of clutch elements to be in engagement at the same time, and independently operable means for disengaging the said second clutch elements whereby the roll may be retained stationary and the shoe moved toward and from the roll.

4. In an ironing machine, a rotatable roll and a shoe, driving mechanism for operating both the roll and the shoe comprising a motor, a pair of clutch elements for connecting and discon-

necting said shoe to and from said motor to move the shoe toward and away from the roll, a second pair of clutch elements independent of said first pair of clutch elements for rotating the roll from said motor, means in connection with the driving mechanism and independent of the movement of the shoe for engaging and disengaging said second clutch elements as an incident to the operation of said first clutch elements, 5 said means enabling both of said pairs of clutch elements to be in engagement at the same time, and independently operable means operable either when the shoe is in engagement with the roll or when disengaged therefrom for disconnecting said second clutch elements whereby the roll may be retained stationary and the shoe moved toward and away from the roll. 10

5. In a device of the class described, a rotatable roll and a movable shoe, driving mechanism for operating both the roll and the shoe comprising a motor, means including a pair of clutch elements for connecting said motor to said shoe to move the shoe toward and away from the roll and for automatically stopping the shoe at either 15 extreme position by automatic disengagement of said clutch elements, a second pair of clutch elements, means in the driving mechanism for automatically operating said second clutch elements as an incident to the operation of said 20 first mentioned clutch elements both when the shoe is moved toward the roll and when the shoe is moved away from the roll, said last mentioned means acting to engage said second clutch elements as said shoe approaches the roll while said 25 first clutch elements are still engaged whereby the roll is automatically connected to said motor when the shoe engages the roll, and said last mentioned means acting to disengage said second clutch elements as the shoe leaves the roll whereby the roll is automatically disconnected 30 from the motor when the shoe leaves the roll, and independent means for disconnecting said second pair of clutch elements when they are in engagement or retaining them in disconnected condition when they are out of engagement whereby the shoe may be moved toward and from the roll without rotating the roll for performing pressing operations. 35

nected from the motor when the shoe leaves the roll, and independent means for disconnecting said second clutch elements and retaining them in such condition whereby the shoe may be moved toward and from the roll without rotating the roll for performing pressing operations. 5

6. In a device of the class described, a rotatable roll and a movable shoe, driving mechanism for operating both the roll and the shoe comprising a motor, means including a pair of clutch elements for connecting said motor to said shoe to move the shoe toward and away from the roll and for automatically stopping the shoe at either extreme position by automatic disengagement of said clutch elements, a second pair of clutch elements, means in the driving mechanism for automatically operating said second clutch elements as an incident to the operation of said first mentioned clutch elements both when the shoe is moved toward the roll and when the shoe is moved away from the roll, said last mentioned means acting to engage said second clutch elements as said shoe approaches the roll while said first clutch elements are still engaged whereby the roll is automatically connected to said motor when the shoe engages the roll, and said last mentioned means acting to disengage said second clutch elements as the shoe leaves the roll whereby the roll is automatically disconnected from the motor when the shoe leaves the roll, and independent means for disconnecting said second pair of clutch elements when they are in engagement or retaining them in disconnected condition when they are out of engagement whereby the shoe may be moved toward and from the roll without rotating the roll for performing pressing operations. 10 15 20 25 30 35

LUTHER RINGER. 40
